PROCESS OF CRACKING MINERAL OIL

Arthur E. Pew, Jr., Bryn Mawr, Pa., assignor, by
mesne assignments, to Houdry Process Corpora-
tion, Wilmington, Del., a corporation of Dela-
ware

Application October 8, 1937, Serial No. 168,012

9 Claims. (Cl. 196—49)

This application is a continuation in part of an application filed by me on the 6th day of March, 1934, Serial No. 714,254.

The cracking of petroleum or of a selected fraction thereof, such as gas oil, is usually effected solely by thermal conversion, although it is well known that cracking is effectively induced and/or promoted by means of many known catalysts, which increase the yield of decomposition products such as gasoline, at a given temperature or give an equal yield of such products at a lower temperature, besides producing, where gasoline is the product, a much better anti-knock gasoline. Usually the oil is heated to effect vaporization and the oil in vapor phase passed through the mass of catalytic material. The temperature of vaporization may be below an effective cracking temperature under purely thermal conditions, but may be well within an effective cracking temperature range in the presence of a catalyst. Or the temperature of vaporization may be high enough and the time of heating long enough to effect some cracking of the vapors before their entry into the catalytic chamber. It is therefore possible to rely solely upon the heat of the entering vapors to produce the thermal conditions required in the catalytic cracking zone to effect the desired cracking. It is also possible to supply heat to the cracking zone to maintain the vapors at or close to their entering temperature.

Notwithstanding the known advantages of cracking in the presence of a catalyst, they do not suffice to overcome the objections thereto, wherefore the commercial practice of such processes is prevented or much restricted.

There are several serious objections to processes involving cracking in the presence of a catalyst wherein reliance is had solely upon the heat of the entering vapors to secure an effective cracking temperature. A serious objection is that there is a continuing drop in the temperature of the oil vapors during their passage through the catalytic chamber. This condition is due to the fact that while the cracking reaction is partly exothermic and partly endothermic, the net reaction is endothermic. A fall in temperature during cracking is a condition precisely the opposite of that required to most efficiently crack. When oil, in either liquid or vapor phase, is raised to a given temperature, cracking proceeds at first at the highest rate possible at that temperature, but such high rate of cracking continues for only a very short period of time, after which the rate of cracking decreases rapidly. If the temperature gradually decreases the rate of

cracking decreases much more rapidly. It is, therefore, apparent that if there is a substantial drop in the temperature of the oil vapors during their passage through the catalytic mass, as there will be if the heat of the entering vapors is solely relied upon to establish the desired temperature of cracking in the contact chamber, a condition precedent to the most effective cracking, namely, a continued maintenance of desired temperature or a progressive rise in temperature during cracking, is not present. It is true that by heating the vapors, before admission to the catalytic mass, to a high cracking temperature, there may be efficient cracking during even a very short passage of the oil vapors through the mass, but this procedure involves substantial cracking of the vapors before they enter the contact chamber. This is objectionable if it is desired to obtain the full advantage of cracking in the presence of a catalyst; and, further the higher the temperature, the more rapid the deterioration of the catalyst, due to carbon deposition on the surfaces of pieces or particles of catalytic material which requires frequent regeneration, usually in situ, by passing an oxygen-containing regenerating fluid therethrough. Indeed, deterioration of the catalyst is a serious problem, since the yield of the lower boiling hydrocarbon mixture desired gradually diminishes, due to deterioration of the catalyst, under any temperature conditions and so rapidly diminishes under high temperature conditions as to make it advisable to carry on the cracking process at a temperature as low as is consistent with a satisfactory yield.

Attempts to transmit heat to the catalytic material so as to prevent a substantial drop of temperature while the oil is passing therethrough have not hitherto been successful, due to the practical difficulty of transmitting enough heat and of imparting such heat uniformly to the entire mass of catalytic material. For example, jacketing the catalytic chamber and flowing superheated steam or hot gases through the jacket is effective only to maintain or raise the temperature of that outer zone of the mass adjacent the hot jacket and is not effective to raise the temperature of the entire mass or to establish substantially uniform temperature conditions throughout the mass.

The object of my invention is to so far eliminate or minimize the objections to the performance of the cracking operation in the presence of a catalyst as to make such mode of cracking commercially practicable. More specifically, the ob-

ject of the invention is to so practice the process as to secure at least as good a yield of the low boiling hydrocarbon desired as with the most efficient purely thermal process and to produce a product which is distinctly superior, in respect to anti-knock qualities, to that produced by any known purely thermal process.

One feature of the process comprises the vaporization of the oil or reactant fluid at a temperature below that which is effective to crack under purely thermal conditions, followed by the passage of the oil into and through a mass of catalytic material which is maintained at a higher temperature than that of the entering vapor; the process also involving such transmission of heat to the mass as to maintain it throughout at about the same temperature so that the temperature of the outflowing cracked gases is above that of the entering gases. Another feature of the process is the passage of the oil vapors through a series of catalytic chambers maintained at progressively higher temperatures, thereby establishing the temperature conditions required to effect maximum cracking. Another feature of the invention is the provision of an endless "ring" of cracking chambers, only one group of which is being employed on stream or in the path of flow of the vapors at any given time, chambers on which contaminants or combustible deposits have accumulated being successively removed from said path and (other) chambers which have been restored to active condition, as by an exothermic regeneration carried out with an oxygen-containing regenerating medium, being successively inserted in said path. The catalytic material in each chamber is regenerated while such chamber or zone is bypassed, and this is done within a controlled temperature range since, as above pointed out, the higher the temperature to which the catalyst is subjected, the more rapidly it deteriorates. In a preferred aspect or embodiment, each chamber, while active, becomes successively one of different groups of chambers and alters its series position in the several groups as the operation progresses, its temperature being accurately regulated in accordance with its series position.

In order that the process may be more clearly understood, and in order, also, to enable the process to be practiced without the necessity of experimentally developing an apparatus for practicing the process, I illustrate in the accompanying drawings a complete cracking plant or conversion and temperature control apparatus adapted to practice the process, as well as desirable structural details of the cracking elements per se.

Figures 1 and 2, taken together, constitute a flow sheet disclosing a complete conversion or cracking unit for practicing my improved process for producing, for example, a lower boiling product from a higher boiling charging stock. Figure 3 is a vertical sectional view of one of the catalytic chambers in which the oil is cracked. Figure 4 is a horizontal section through a part of said chamber. Figure 5 is a diagram of one arrangement of catalytic chambers. Figure 6 is a diagram of another arrangement of catalytic chambers.

1 indicates a line through which charging stock, fed to the apparatus, flows through heat exchangers 2 and 3, wherein it is partially heated by stock flowing from a later stage in the process, as will hereinafter be described. The pump 6 picks up the preheated stock flowing through line

1 and passes it under pressure through line 9 to the heating coil 8 within the tube still 7.

From the heating coil 8 the stock is passed through line 11 to a vaporizer 12. Within the vaporizer 12 the heated stock expands into vapor and passes upwardly through the trays which are diagrammatically illustrated. A portion of the vapors is withdrawn from the top of the vaporizer through line 14 and passes through condenser 15. The condensed liquid is then pumped back to the vaporizer through line 17 by means of pump 16 to serve as reflux liquid within the vaporizer. A stock which is not vaporized on entering the vaporizer, or which is condensed on the trays, is drawn off through line 13 from the bottom of the vaporizer.

The vapors to be further treated pass off through line 18 at the top of vaporizer 12, and pass through separator 19 in which entrained droplets are removed by mechanical means such as baffles, etc. These entrained droplets fall to the bottom of the separator and pass by gravity through line 20 to the bottom portion of the vaporizer 12 and thence through line 13.

25 The vapors which, as far as possible, have now been freed of entrainment, leave the separator through line 21 and pass through expansion valve 22 and thence through a Venturi tube 23 or any other appropriate mixing device. A line 30 24 is also connected to mixing device 23 for the admission of superheated steam or heated dry hydrocarbon or other inert gas such as carbon dioxide or flue gas.

From the mixer 23 a line 26 leads to a coil 29 within a furnace 28. From the coil 29 a line 30 leads to a cracking apparatus, which may be a single chamber or, very much preferably, comprise a series of chambers 31, 32 and 33, arranged or joined as shown or in other desired manner, or a "ring" of chambers 91 to 102 as shown in Fig. 6. These chambers, which include the most important elements required for the practice of the process, are hereinafter described in detail. A by-pass line 27 connects lines 26 and 30. Lines 45 26, 27 and 30 are provided with suitable valves so that all vapors flowing from mixing device 23 may completely or partially by-pass the heating coil 29.

The cracked vapors leaving the cracking chamber, or any one or more of the chambers of the series, pass through line 37 to a distillation tower 38, wherein they may be fractioned to produce, for example, an overhead gasoline vapor cut, a side stream which may be heavy naphtha or light 55 gas oil, and a bottoms.

The side stream is withdrawn through line 5 and is passed through heat exchanger 2, while the bottoms are withdrawn through line 4 and passed through heat exchanger 3, both the side stream and bottoms giving up their heat in these exchangers to preheat the stock flowing to this system.

The overhead vapor cut is removed from the tower through line 39 and passes to a clay tower 47, wherein the vapors are purified by contact with fuller's earth, bentonite, or like treating or chemical stabilizing medium. The purified vapors pass from the clay tower 47 through line 49 to a condenser 50 and the condensed liquid is then passed to the product accumulator 51. The polymer fraction which is formed in clay tower 47 is withdrawn through line 48.

In order to provide for reflux within the distillation tower 38, a portion of the overhead vapor cut passing through line 39 is withdrawn

through line 40 and passed through condenser 41 to reflux accumulator 42. From the reflux accumulator 42 the condensed and cooled reflux stock is withdrawn through line 43 by means of pump 44 and is forced to the top of the tower 38. The permanent gases which are not condensed in the condenser 41 are withdrawn from the reflux accumulator 42 by means of line 46 and any surplus reflux liquid may be withdrawn through line 45.

The final product is withdrawn from the accumulator 51 through line 53. The fixed gases not condensed within condenser 50 are withdrawn from the product accumulator 51 through line 52.

Each of the cracking chambers 31, 32 and 33 (see Figs. 3 and 4) may take the form of a cylindrical casing 60 provided with tube sheets providing top and bottom headers or manifolding chambers 61 and 62 and between them the reaction zone or catalytic cracking chamber, which is substantially filled (except for the space occupied by the tubes hereinafter described) with bentonite, bauxite, fuller's earth, or any other siliceous or adsorptive catalyst (e. g. in the form of pieces or particles) which has been or may be found effective for the reaction desired, these catalysts being preferably in activated form rather than in their natural condition. A multiplicity of tubes 64 extends between the tube sheets and are closed at the bottom and are open at the top to allow the extension therewithin of vapor inlet tubes 63, whose upper ends extend through the upper tube sheet and communicate with upper header 61. Each tube 63 is in concentric or telescopic relation with a corresponding tube 64 and extends down to nearly the lower end of tube 64 and there opens into tube 64. A multitude of vapor outlet tubes 65 are carried by and extend through the lower tube sheet and there communicate with lower header 62. These tubes extend upward throughout nearly the entire height of the chamber and are closed at the top. Tubes 64 and 65 have perforated walls, and each tube 64 has spaced from it, at short distances and in symmetrical relation, a number of tubes 65 so that oil vapors passing from tube 30 through header 61 and tubes 63 into tubes 64, pass laterally through the perforations in tubes 64, thence through the catalytic material with which the chamber is packed, thence through the perforations in tubes 65 into such tubes, thence through such tubes into header 62 and thence through pipe 67 away from the reaction zone, and may pass to the next catalytic chamber of the series, as desired. After passing through any additional treating or reaction zone, or not, as the particular circumstance dictates, e. g. through chamber 32, pipe 68 and chamber 33, the finally cracked vapors pass through pipe 37 to the fractionating tower 38.

The casing 60 of each cracking chamber should be insulated from the surrounding atmosphere by any suitable means such as a jacket 69 for hot gases or by insulating material. In case the insulating function is effected by hot gases, these need not impart any heat to the chamber, since heat so applied does not penetrate the mass of catalytic material or does not penetrate it to the extent required to establish and maintain uniform heat conditions throughout the mass. Such uniform heat conditions are effected, preferably, by means of a heat exchange fluid, such as mercury, or any other equivalent substance, flowing through a multitude of tubes 70, which,

when introduced to the tubes 70, is so close to its temperature of condensation that, in the endothermic reaction, it can, when introduced to the tubes 70 in vapor phase, impart heat to the mass by condensation, while, in the exothermic reaction, it can, when introduced to the tubes 70 in liquid phase, extract heat from the mass by vaporization.

Apparatus applicable to the present case is disclosed in various patents heretofore issued to me, for example, in Nos. 1,714,811 and 1,714,812, issued May 28, 1929. The main features of such apparatus are shown in Fig. 3. Mercury from a reservoir or boiler 71 flows through a pipe 72, controlled by a valve 73, into a header 74 and thence into and through tubes 70, thereby to effect heat exchange with and control the temperature of the contact material or catalyst in the chamber 31, 32 or 33. Where the mercury or other heat exchange fluid is giving up heat to the contact material, as in the aforementioned illustrative on-stream or endothermic reaction, rather than absorbing or withdrawing heat therefrom as would be the case in controlling an exothermic reaction such as the above indicated step of regeneration within a restricted temperature range, the heat exchange fluid may be supplied partly or entirely in vapor phase, condensate forming and yielding up heat to the contact material. Condensed or liquid mercury or like fluid, often accompanied by some vapors, flows from heat exchange tubes 70 into header 75 and thence through a pipe 76 into a gas trap 77, provided with a relief valve 78, and thence through pipe 79 back to the reservoir or boiler 71. Valve 73 may be operated to control the rate of flow of mercury, thereby regulating the pressure within tubes 70 and thus regulating the temperature at which a heat exchange fluid such as mercury will change state, i. e. will change from vapor to liquid or from liquid to vapor. It is thereby possible, as illustrated more fully in said patents, to progressively increase the temperatures in the pipes 70 of successive catalytic chambers while maintaining the mercury, or like heat exchange medium, under conditions so that the same is at least to substantial extent in a liquid or condensed state, thereby maintaining such chambers at progressively higher temperatures. The pressure in the reservoir or boiler 71 may, for convenience, be maintained at least as high as the desired pressure in the pipes 70 of any of the catalytic chambers which it may be desired to heat to a higher temperature than the others, e. g., the last chamber 33 of the series, and may, be higher than the desired pressure in the pipes 70 of chambers 32 and 33. The difference in pressure in such a system between the boiler pressure and the pressure in any group of pipes 70 may be taken care of by the balancing columns of liquid mercury in the pipe 76, the height of the left hand column automatically rising above that of the right hand column until the difference in the heights of the two liquid columns balances the said difference in vapor pressure.

The heating system described is admirably adapted to provide a substantially precise control of the temperature or temperature range of any of the catalytic chambers, so as, for example, to maintain the same substantially at desired temperature and to provide for continuously maintaining substantially uniform or desired temperatures throughout all portions of the mass or bed of contact material. In general, the tem-

perature of heat exchange liquid or medium which is flowed in direct heat conducting relation with the body of contact material, as through pipes 70, will be introduced into the latter at a temperature approaching that desired in the contact material and departing from the latter temperature sufficiently only to effect the desired amount of heat exchange with the contact material while avoiding, when desired, any substantial difference in the temperature of contact material adjacent opposite ends of pipes 70. Pipes 70, or tubes 64 and 65 taken in connection with pipes 70, when such tubes are employed, divide the body of contact material into a plurality of elongate intercommunicating reaction zones, which facilitates desired temperature control of all portions of the contact or catalytic material, regardless of the particular manner in which fluid reactants are passed through and in contact with such material. This permits reactant fluids or products and/or regenerating medium to pass from one elongate reaction zone to another, where desired, in their passage through the contact material.

A valve-controlled pipe 34 connects with vapor inflow pipe 30 and a valve-controlled pipe 35 connects with vapor outflow pipe (67, 68, or 37). After the cracking-inducing capacity of the catalytic material of any chamber becomes impaired, the valves controlling pipes 30 and 37 may be closed and the valves controlling pipes 34 and 35 opened, and suitable gas blown through pipe 34, header 61, tubes 63, 64 and 65, header 62 and pipe 35, in order to regenerate the contact material. Such regeneration comprises, mainly, the removal, usually in situ, of superficially deposited carbon from the contact material or catalyst and need not be particularly described, other than to say that it is intended to maintain the catalytic material within a suitable temperature range so as to avoid deterioration due to high temperatures as by heat exchange with a suitable medium as above described and illustrated.

I shall briefly illustrate the operation of the apparatus above described and shall, as a matter of illustration and not of limitation, specify certain pressures, temperatures and modes of operation. It must be understood that such specific conditions need not be adhered to in actual practice, as the most desirable temperatures and pressures and other conditions will vary with the particular charging stock, and even in the case of a given charging stock will vary with the desired product.

The charging stock, which may be gas oil, is fed through the heating coil 8. A pressure of 100 pounds gauge is imposed on the gas oil by means of pump 6. A temperature of slightly over 850° F. is imparted to the charging stock in passing through coil 8. The heated stock then flows into vaporizer 12, within which it is partly freed from entrainment by passing counter-current to the reflux liquid flowing down over trays therein. The vapors then flow into separator 19, wherein they are further dried by mechanical means. The vapors then pass through line 21 to the expansion valve 22, where they are expanded to a pressure approximating 15 pounds gauge. At this time their temperature will have dropped due to their expansion to about 775° F. This sudden expansion of heated vapors serves to thoroughly dry them. To make sure that no mist or small droplets remain in the vapors, superheated steam or other dry gas, such as dry hydrocarbon vapors or carbon dioxide, heated to about

5 the same temperature as the oil vapors, is mixed with the oil vapors in the mixer 23, and, by the partial pressure effect, insures the thorough drying of the oil vapors. Usually, either the described sudden expansion of the oil vapors or the described addition of a dry gas will insure the thorough drying of the vapors.

10 The dried vapors are then quickly superheated in the vapor heater 29 to a temperature of 850° F. and thence pass direct to the catalytic chamber 31. At this temperature the rate of cracking, under purely thermal conditions, is comparatively slow and the duration of heating is so short that no substantial cracking occurs in the vapor heater. The possible range of temperature to within which the vapors may be heated in heater 28 is fairly wide, even with a given charging stock. It is desirable, however, to heat the vapor to so low a temperature and/or for so short a time as to prevent a material amount of cracking, although, less desirably, a limited amount of cracking may occur in the heater 28. Preferably, the temperature should closely approximate that in the first cracking chamber, since the capacity of the catalyst to induce cracking is so great that it is possible to effect, in the catalytic chamber, what would ordinarily be considered complete cracking, at a temperature at which substantially no cracking is effected in heater 28. Thus, very effective cracking of the vapors may be effected in a single catalytic chamber 31 at a temperature of between 820° and 850° F., and such low temperatures therein are often desirable, since the lower the temperature therein, the longer the time during which it is economically practicable to operate without regeneration of the catalyst. Thus, if the cracking temperature in chamber 31 be maintained between 820° and 850° F., the oil vapors may be heated in heater 28 fairly close to but below the temperature in chamber 31. If, however, the vapors entering chamber 31 are in a thoroughly dry condition, it is practicable to crack at considerably higher temperature. Even if the vapors be not thoroughly dried, it is permissible to crack in chamber 31 at a temperature considerably higher than that of the entering vapors and considerably higher than a temperature of 850° F., although in such case the catalyst will deteriorate more rapidly. It may be assumed, therefore, that the oil vapors enter chamber 31 at a temperature of 850° F. and are therein subjected to a temperature of 860° F., at which temperature, with a fresh catalyst, the yield of gasoline will be about 40 per cent. more or less, depending on the particular charging stock and all conditions of operation.

15 It is clear, from the foregoing description, that the process is of great advantage if but one catalytic chamber is employed; and a process involving the use and temperature control of one such chamber, as herein illustrated and described, is within the broader field of my invention. However, as hereinbefore explained, a maximum cracking effect cannot be achieved by subjecting oil to a constant, however, high, cracking temperature, but can only be achieved by raising the temperature, throughout a temperature cracking zone, gradually or by increments. By providing a series of such cracking chambers, and passing the oil vapors therethrough successively, at temperatures (say) of 860° F., 880° F. and 900° F. successively, a very thorough cracking is effected, giving not only a very high yield of gasoline, but producing a gasoline having high anti-knock quality.

It will be understood that the series of three catalytic cracking chambers is merely illustrative of a series of any number. The greater the number of such chambers in the series, the more efficient the cracking operation from the point of yield. The number is limited, however, by considerations such as cost of installation and maintenance.

It should be stated that the use of a special vapor heater 28 is not imperative, since it is possible to heat the oil to the required temperature in coil 8; or, what is more practicable, to so superheat the dry gas admitted at the mixer 23 that it will supply the heat that would otherwise be supplied in the special heater 28. If heat is so added, the oil vapors will be by-passed, through pipe 27, to pipe 30 and the catalytic chamber 31.

In any process involving cracking in the presence of a really effective catalyst, the efficiency of the catalyst becomes impaired as the process proceeds, with a resultant gradual reduction in yield of the desired product. It is, therefore, desirable to maintain the catalyst in continuous use for a relatively short time and to then cut it out of operation and regenerate it. I diagrammatically show, in Fig. 5, three series of catalytic chambers, namely 80, 81, and 82, each series comprising three or more chambers. One series only is in operation during any given time. While one series is in operation, the other two series are undergoing regeneration. The time required for regeneration is usually approximately equal to the time during which the catalyst is in the oil circuit, so that the provision of three (or more) series of catalytic chambers not only gives ample time for regeneration, but provides for maintaining any series in circuit for so comparatively short a time that it may be cut out of the oil circuit before its efficiency becomes seriously reduced. The heated oil vapors flow from pipe 30 into a header 33 (Fig. 5) and thence successively through the catalytic chambers of one of the series 80, 81, and 82 and thence into header 84 and into pipe 37. After the lapse of a given time (say two hours), the active series is cut out of the oil circuit and one of the other series is brought into the oil circuit, by obvious manipulation of valves which need not be described. Then the second series is cut out of the oil circuit and the third series brought into the oil circuit. Then the first arrangement is re-established.

While such arrangement and operation are entirely practicable, it is obvious that to the extent that the yield drops during the continuation of the operation of any given catalytic chamber or series of chambers, to that extent the yield will vary during the operation of the plant. To secure an approximately constant yield I carry out the process in the following manner. An endless ring of catalytic cracking chambers is provided. The hot vapors from heater 28 pass successively through a group of (say) three chambers and bypass the remaining chambers. After the lapse of a given time, one of the active chambers is removed from the oil circuit and one of the previously inactive chambers, which has been restored to active condition by regeneration, after the lapse of a given time interval, is carried on indefinitely. There is thus in circuit, just after each change, three chambers, one chamber containing fresh

5 catalyst, another that has been in operation during one time unit and another that has been in operation during two time units. The greater the number of chambers in operation during each time unit, the more nearly constant will be the yield and character of products from the apparatus.

In Fig. 6 is shown in diagram an apparatus adapted to carry out the process in accordance with the immediately preceding description. Twelve catalytic chambers, 91 to 102 inclusive, are shown. The hot oil vapors flow from pipe 30 into a header 103. Each catalytic chamber is connected with the header 103 by a valve-controlled vapor inflow pipe 104. Each chamber is provided with an outlet pipe 105 having valve-controlled branches 106 and 107 communicating respectively with the vapor inflow pipe 104 of the next chamber of the series and with a header 108 for outflowing cracked vapor.

20 Let it be assumed that the valves are so operated as to cause the hot oil vapors to flow from pipe 30 and header 103 through chambers 91, 92 and 93 successively and thence to header 108 and pipe 37. After a given time interval the necessary valves are manipulated to cut out chamber 91 and shift the flow through chambers 92, 93 and 94. After another equal time interval the necessary valves are operated to cut out chamber 92 and shift the flow through chambers 93, 94 and 95; and so on throughout the ring.

25 If it be assumed, but only for convenience of illustration, that it is desired to maintain each chamber in operation for three consecutive hours and to maintain three chambers always in operation, it will be understood that the several chambers may be in operation during the following periods. Chamber 91 from 12 to 3 o'clock, chamber 92 from 1 to 4, chamber 93 from 2 to 5, chamber 94 from 3 to 6, chamber 95 from 4 to 7, chamber 96 from 5 to 8, chamber 97 from 6 to 9, chamber 98 from 7 to 10, chamber 99 from 8 to 11, chamber 100 from 9 to 12, chamber 101 from 10 to 1 and chamber 102 from 11 to 2. Chambers 30 91, 92, and 93 will be simultaneously in operation from 2 to 3 o'clock, chambers 92, 93, and 94 from 3 to 4, chambers 93, 94, and 95 from 4 to 5, chambers 94, 95 and 96 from 5 to 6, chambers 95, 96, and 97 from 6 to 7, chambers 96, 97 and 98 from 7 to 8, chambers 97, 98, and 99 from 8 to 9, chambers 98, 99 and 100 from 9 to 10, chambers 99, 100 and 101 from 10 to 11, chambers 100, 101 and 102 from 11 to 12, chambers 101, 102 and 90 from 12 to 1 and chambers 102, 91 and 92 from 55 1 to 2.

55 It is obvious that a greater number of chambers may be included in the active series during any given hourly (or other) period, and that the total number of chambers may be increased or diminished. The specific illustration given provides more than ample time for effecting regeneration of the catalytic material contained in any chamber during its period of inactivity. By so carrying on the process, a nearly constant efficiency of the process may be maintained, with a nearly constant yield of the desired low boiling product.

60 It is obvious that the pipe connections to the ring of catalytic chambers may be so arranged that the chamber which, at the expiration of each hourly (or other period) is brought into the oil vapor circuit may operate as the first, instead of the last, consecutive chamber of the newly established circuit; and that the chamber which, at 65 the expiration of each hourly (or other) period, is

cut out of the oil vapor circuit, will be the chamber that is functioning as the last, instead of the first, consecutive chamber of the series.

While I have applied the term "ring" to the arrangement of contact chambers shown in Fig. 6 and have therein illustrated a ring-like arrangement, it will be understood that the actual structural arrangement may have no resemblance to a "ring," although the word may be even then apt to apply to the process actually carried out in any structural arrangement.

While the hereinbefore described specific example of the process is of the cracking of gas oil to gasoline, the process is also applicable to the cracking or transformation of heavy naphtha, kerosene, fuel oil and (exceptionally) gasoline or a gasoline fraction, and the desirable reaction temperature will vary with the charging stock, being, for example, usually progressively higher in the case of cracking of progressively lighter fractions.

What I claim and desire to protect by Letters Patent is:

1. The process of cracking the vapors of a mineral oil charging stock which comprises heating the vapors to within a temperature range within which no efficient cracking occurs during said heating period but within which range rapid and efficient cracking would occur during such period in the presence of the catalyst hereinafter specified, and then flowing said heated vapors through a mass of adsorptive catalytic material adapted to induce such rapid and efficient cracking within said temperature range, and while the oil vapors are so flowing within said mass supplying heat thereto to compensate for that absorbed by the net endothermic cracking reaction and thereby maintain the oil vapors throughout their entire flow through said mass at a temperature within said range by transfer of heat from a multiplicity of symmetrically disposed streams of heating medium flowing through but out of contact with the catalytic material so that the cracked vapors leave the mass at a temperature within said range and not below that of their entry thereto.

2. The process of cracking the vapors of a mineral oil charging stock which comprises heating the vapors to within a temperature range within which no efficient cracking occurs during said heating period but within which range rapid and efficient cracking would occur during such period in the presence of the catalyst hereinafter specified, and then flowing said heated vapors through a mass of adsorptive catalytic material adapted to induce such rapid and efficient cracking within said temperature range, and while the oil vapors are so flowing within said mass supplying enough heat thereto to more than compensate for that absorbed by the net endothermic cracking reaction and thereby raise the temperature of the oil vapors during their flow through said mass by transfer of heat from a multiplicity of symmetrically disposed streams of heating medium flowing through but out of contact with the catalytic material so that the cracked vapors leave the mass at a temperature within said range appreciably above that of their entry thereto.

3. The process of cracking the vapors of a mineral oil charging stock which comprises heating the vapors to within a temperature range within which no efficient cracking occurs during said heating period but within which range rapid and efficient cracking would occur during such

period in the presence of either of the catalytic masses hereinafter specified, and then flowing said heated vapors successively through a plurality of cracking chambers, the catalyst in each chamber comprising a mass of adsorptive catalytic material adapted to induce cracking and while the vapors are so passing within each cracking chamber so supplying heat thereto by transfer of heat from a multiplicity of symmetrically disposed streams of heating medium flowing through but out of contact with the catalytic material as to at least compensate for that absorbed by the net endothermic cracking reaction and thereby prevent the reduction in temperature therein that would otherwise occur.

4. The process of cracking the vapors of a mineral oil charging stock which comprises heating the vapors to within a temperature range within which no efficient cracking occurs during said heating period but within which range rapid and efficient cracking would occur during such period in the presence of either of the catalytic masses hereinafter specified, and then flowing said heated vapors successively through a plurality of cracking chambers, the catalyst in each chamber comprising a mass of adsorptive catalytic material adapted to induce cracking and while the vapors are so passing within each cracking chamber so supplying heat thereto by transfer of heat from a multiplicity of symmetrically disposed streams of heating medium flowing through but out of contact with the catalytic material as to somewhat more than compensate for that absorbed by the net endothermic cracking reaction so that the cracked vapors leave each chamber at a temperature within said range appreciably above that of their entry thereto.

5. The process of cracking the vapors of a mineral oil charging stock which comprises heating the vapors to within a temperature range within which no efficient cracking occurs during said heating period but within which range rapid and efficient cracking would occur during such period in the presence of the catalyst hereinafter specified, then flowing said heated vapors through a mass of adsorptive catalytic material adapted to induce such rapid and efficient cracking within said temperature range and during the catalytic cracking operation flowing a heating medium through and in direct heat exchange relation, but out of contact, with the catalytic mass, said heating medium being at such temperature as to supply enough heat to the mass to at least compensate for the heat absorbed by the net endothermic cracking reaction and traveling through the mass in the form of a multitude of fine closely associated independent streams distributed with substantial uniformity throughout the mass, whereby all parts of the mass are heated with substantial uniformity and the cracked vapors leave the mass at a temperature not appreciably below the temperature of their entry into the mass.

6. The process of cracking the vapors of a mineral oil charging stock which comprises heating the vapors to within a temperature range within which no efficient cracking occurs during said heating period but within which range rapid and efficient cracking would occur during such period in the presence of the catalyst hereinafter specified, then flowing said heated vapors transversely through an upright cylindrical mass of adsorptive catalytic material adapted to induce such rapid cracking within said temperature range and during the catalytic cracking opera-

tion supplying enough heat to the catalyst while the oil vapors are flowing therethrough to compensate for that absorbed by the net endothermic cracking reaction by flowing substantially vertically through the catalytic mass, in direct heat conducting relation therewith but out of contact therewith, a heating medium in a multiplicity of closely associated and evenly distributed independent fine streams so that all parts of the mass are heated with substantial uniformity and the cracked vapors leave the mass at a temperature within said range and not below the temperature of their entry into the mass.

7. In a process for the chemical treatment or transformation of hydrocarbon fluid in the presence of solid porous adsorptive and incombustible contact material within a reaction space in which said contact material is alternately employed on stream to effect the desired transformation of said hydrocarbon fluid and in regeneration in situ by passing a regenerating fluid therethrough to effect removal of combustible deposits therefrom, the cycle of operation involving a period on stream and a period in regeneration being repeated over and over, the method of heat exchange and temperature control which comprises flowing each of said fluids, alternately one with the other, within but out of contact with the bed of contact material in a multiplicity of parallel vertical streams and thence through the contact material and thence flowing the transformed fluid in a multiplicity of parallel vertical streams within but out of contact with the bed of contact material, the vertical streams of each set being symmetrically arranged at variable distances from the vertical center line of the bed and the streams of the two sets being so symmetrically arranged relatively to each other as to provide a multiplicity of paths of fluid flow through the bed of contact material between vertical inflow and outflow streams that are spaced apart a distance short relative to the lateral dimensions of the contact bed, and simultaneously flowing a heat exchange fluid through the mass of contact material in direct heat conducting relation but out of contact with said contact material and at a temperature approaching that which it is desired to maintain in said contact material and deviating from the latter temperature substantially only to effect the desired amount of heat exchange therewith, the temperature of the heat-exchange fluid during the on-stream cycle being such as to supply enough heat to the mass to compensate for the heat absorbed by said net endothermic reaction, said heat exchange fluid being a material extraneous to said reactant and regenerating fluids and flowing vertically through the bed of contact material in a multitude of independent streams at variable distances from the center line of the bed and symmetrically arranged with respect to each other and to the vertically flowing fluid inlet and outlet streams, and subjecting the transformed hydrocarbon fluid to further reformation in another contact chamber in which the flow of such hydrocarbon fluid and the flow of a heat exchange medium is the same as in the first chamber but in which the temperature of the heat exchange medium is sufficiently high to maintain in the contact mass a uniform temperature above that maintained in the first contact mass, thereby insuring in the second treatment the subjection of all the hydrocarbon fluid to a temperature above that to which it is subjected in the first treatment.

8. In a process for the chemical treatment or transformation of fluid hydrocarbon reactants in the presence of solid porous adsorptive and incombustible contact material within a reaction space in which said contact material is alternately employed on-stream to effect the desired transformation of reactants with accompanying net endothermic reaction and in regeneration in situ by passing a regenerating fluid therethrough to effect removal of combustible deposits therefrom, the cycle of operation involving a period on-stream and a period in regeneration being repeated over and over, the method of heat exchange and temperature control which comprises flowing each of said fluids within but out of contact with the bed of contact material in a multiplicity of parallel vertical streams and thence through the contact material and thence flowing the transformed fluid in a multiplicity of parallel vertical streams within but out of contact with the bed of contact material, the vertical streams of each set being symmetrically arranged at variable distances from the vertical center line of the bed and the streams of the two sets being so symmetrically arranged relatively to each other as to provide a multiplicity of paths of fluid flow through the bed of contact material between vertical inflow and outflow streams, and subjecting the transformed hydrocarbon fluid to further reformation in another contact chamber in which the flow of such hydrocarbon fluid and the flow of a heat exchange medium is the same as in the first chamber but in which the temperature of the heat exchange medium is sufficiently high to maintain in the contact mass a uniform temperature above that maintained in the first contact mass, thereby insuring in the second treatment the subjection of all the hydrocarbon fluid to a temperature above that to which it is subjected in the first treatment.

9. In a process for the chemical treatment or transformation of fluid hydrocarbon reactants in the presence of solid porous adsorptive and incombustible contact material within a reaction space in which said contact material is alternately employed on stream to effect the desired transformation of reactants with accompanying net endothermic reaction and in regeneration in situ by passing a regenerating fluid therethrough to effect removal of combustible deposits therefrom with accompanying net exothermic reaction, the cycle of operation involving a period on stream and a period in regeneration being repeated over and over, the method of heat exchange and temperature control which comprises flowing each of said fluids within but out of contact with the bed of contact material in a multiplicity of parallel vertical streams and thence through the contact material and thence flowing the transformed fluid in a multiplicity of parallel vertical streams within but out of contact with the bed of contact material, the vertical streams of each set being symmetrically arranged at variable distances from the vertical center line of the bed and the streams of the two sets being so symmetrically arranged relatively to each other as to provide a multiplicity of paths of fluid flow through the bed of contact material between vertical inflow and outflow streams, and subjecting the transformed hydrocarbon fluid to further reformation in another contact chamber in which the flow of such hydrocarbon fluid and the flow of a heat exchange medium is the same as in the first chamber but in which the temperature of the heat exchange medium is sufficiently high to maintain in the contact mass a uniform temperature above that maintained in the first contact mass, thereby insuring in the second treatment the subjection of all the hydrocarbon fluid to a temperature above that to which it is subjected in the first treatment.

streams that are spaced apart a distance short relative to the lateral dimensions of the contact bed, and simultaneously flowing heat exchange fluid through the mass of contact material in direct heat conducting relation but out of contact with said contact material and at a temperature approaching that which it is desired to maintain in said contact material and deviating from the latter temperature substantially only to effect the desired amount of heat exchange therewith, the temperature of the heat-exchange fluid during the on-stream cycle being such as to supply enough heat to the mass to compensate for

the heat absorbed by said net endothermic reaction, the temperature of the heat exchange fluid during the regenerating cycle being such as to extract heat from the mass, said heat exchange fluid being a material extraneous to said reactant and regenerating fluids and flowing vertically through the bed of contact material in a multitude of independent streams at variable distances from the center line of the bed and symmetrically arranged with respect to each other and to the vertically flowing fluid inlet and outlet streams.

ARTHUR E. PEW, JR.
